CLAIM

The ornamental design for a transfer robot as shown and described.

DESCRIPTION

FIG. 1 is a perspective view from the front, right side of a first embodiment of a transfer robot according to our design; FIG. 2 is a perspective view from the rear, right side thereof;

FIG. 3 is a top view thereof;

FIG. 4 is a bottom view thereof;

FIG. 5 is a view of the left side thereof;

FIG. 6 is view of the right side thereof;

FIG. 7 is a front view thereof;

FIG. 8 is a rear view thereof;

FIG. 9 is a perspective view from the front, right side of a second embodiment of a transfer robot according to our design;

FIG. 10 is a perspective view from the rear, right side thereof;

FIG. 11 is a top view thereof;

FIG. 12 is a bottom view thereof;

FIG. 13 is a view of the left side thereof;

FIG. 14 is view of the right side thereof;

FIG. 15 is a front view thereof; and,

FIG. 16 is a rear view thereof.

The broken lines depict portions of the transfer robot in which the design is embodied that form no part of the claimed design.
